CAR ROOF

William E. Bikle, Park Ridge, Ill., assignor, by
mesne assignments, to Standard Railway
Equipment Manufacturing Company, a corpora-
tion of Delaware

Application June 28, 1937, Serial No. 150,840

4 Claims. (Cl. 108—5.4)

The invention relates to car roofs and has more particular reference to a common means for supporting the running board above the roof and a ceiling beneath the same. To this end, the invention consists in the construction as herein-after set forth.

In the drawing:

Figure 1 is a vertical cross section through a portion of a car roof showing my improvement applied thereto;

Figure 2 is a longitudinal section on line 2—2 of Figure 1;

Figure 3 is a similar view showing a slightly modified construction;

Figure 4 is a sectional plan view taken substantially on line 4—4 of Figure 1.

In the present state of the art, running boards are usually mounted upon the roof through the medium of saddles which extend across the ridge. These saddles are connected to the roof in various ways and at their upper ends are provided with a flange or shelf to which the running boards are attached. Certain constructions of cars are also provided with a ceiling beneath the roof attached thereto by hangers. With my improved construction portions of the saddle are extended through the roof and form the hangers for supporting the ceiling.

In detail, A is a car roof which is formed of adjacent roofing sheets having vertical flanges B welded to each other. On opposite sides of the ridge these flanges B have pressed or otherwise formed therein recesses for the passage through the roof of a member C. This member has a portion C¹ of a width and thickness to fit within said recess and of a length to project a predetermined distance beneath the roof. Above the portion C¹ is a portion C² of greater width forming shoulders C³ for resting on the roof, said portion extending upward a predetermined distance above the roof. D is a bridge member extending between the members C and secured thereto at its opposite ends. As shown in Figure 2, the member D is in the form of an angle bar, the vertical flange of which is secured to the portion C² of the member C by bolts D¹. In the modified construction shown in Figure 3, the portion C² is provided with a laterally extending flange C⁴ to which the bridge member D is bolted, as indicated at D². The member D forms a direct support for the running board E attached thereto by bolts E¹, while the upwardly extending portion C² of the member C forms the support for the member D. The portion C¹ depending beneath the roof has a strip F attached thereto, preferably at one side thereof,

by means of a bolt G or other securing means. This strip extends transversely of the roof being further attached thereto by additional hangers H. I is the ceiling shown as formed of match boards which are nailed or otherwise fastened to the strip F.

After the roofing sheets are assembled and their flanges B welded to each other, the member C may be inserted through the recesses and then secured and sealed by welding along both sides thereof. The hangers H may also be attached to the roof at such time. However, the mounting of the running board and the placing of the ceiling may be performed at any time subsequent to the forming of the roof and without additional brackets or hangers.

While I have described separate members C on opposite sides of the ridge, it is obvious that these might be made integral with a member extending across the ridge provided with the depending portions C¹.

What I claim as my invention is:

1. In a metallic car roof, a member extending through said roof and supported thereby having a portion depending beneath the same forming a ceiling support, and a portion extending upward for supporting a running board.

2. In a car roof, the combination with roofing sheets having abutting vertically extending flanges secured to each other, of a member extending between said flanges and supported thereby having a portion above the roof for supporting a running board, and a portion depending beneath the roof for supporting a ceiling.

3. In a car roof, the combination with roofing sheets having vertically extending abutting flanges secured to each other, of a pair of members upon opposite sides of the ridge extending between said flanges and supported thereby having portions depending beneath the roof forming a ceiling support, and portions extending above the roof forming a support for the running board.

4. In a car roof, the combination with roofing sheets having vertically extending abutting flanges secured to each other, of a pair of members upon opposite sides of the ridge extending between said flanges and supported thereby having portions depending beneath the roof forming a ceiling support, portions extending above the roof, and a bridge member secured to and extending between said portions extending above the roof and forming a support for the running board.

WILLIAM E. BIKLE.
